GARMENT BAGGING RACK

Leslie T. Hinnant, Goldsboro, N.C.

Application February 12, 1948, Serial No. 7,977

1 Claim. (Cl. 222-18)

1

This invention comprises novel and useful improvements in a garment bagging rack and more specifically pertains to an apparatus to facilitate the placing of garments and similar articles in paper bags or the like.

It is a primary object of this invention to provide an apparatus which will facilitate and assist the placing of garments in paper bags in a convenient and time-saving manner.

An important feature of the invention resides in the provision of a stand having support columns for supporting garment hangers, together with bag-supporting means disposed above the support column.

A further feature of the invention resides in the provision of an apparatus as set forth in the preceding paragraph wherein an extension is provided for selectively lengthening the garment supports as desired.

A still further feature of the invention resides in the provision of a novel bag support rack wherein a plurality of bags of different sizes to accommodate different types of garments may be individually supported in a position elevated above the garment support.

A further important feature of the invention resides in the provision of an apparatus in accordance with the preceding objects and features wherein the bag-supporting racks are disposed in parallel relation at different elevations and alternatively face laterally or longitudinally from each other.

These, together with various ancillary features and objects of the invention which will later become apparent as the following description proceeds, are attained by this device, preferred embodiments of which have been illustrated by way of example only in the accompanying drawings, wherein:

Figure 1 is a perspective view of one embodiment of the invention, the position of a garment hanger upon its support rod, a bag placed thereover, and various supplies of bags suspended from the bag rack all being indicated in dotted lines;

Figure 2 is an end elevational view of the arrangement shown in Figure 1, parts being broken away;

Figure 3 is an enlarged front elevational view of the garment bag supporting rack shown in Figure 1, an alternative position of the same being indicated in dotted lines therein;

Figure 4 is a perspective view of a second embodiment of the invention;

Figure 5 is a vertical sectional view taken upon the plane of the section line 5-5 of Figure 4;

2

Figure 6 is a fragmentary detail view taken upon an enlarged scale substantially upon the plane of the section line 6-6 of Figure 4, and illustrating the locking means of an extensible garment support;

Figure 7 is a fragmentary detail view taken upon an enlarged scale substantially upon the plane of the section line 7-7 of Figure 6;

Figure 8 is an enlarged fragmentary detail view taken in elevation and showing the garment bag retaining means, an alternative position thereof being indicated in dotted lines; and

Figures 9 and 10 are fragmentary front and rear elevational views, respectively, of a garment support rod and its telescoping extension showing the locking means therefor.

Referring now more specifically to the accompanying drawings, and first to the embodiment of the invention illustrated in Figures 1-3, the

10 numeral 10 indicates a base which may be of any suitable shape and material, one satisfactory construction being generally rectangular in shape and formed of metallic strips welded or otherwise rigidly secured together. From intermediate the 20 base 10, there arises a socket member 12 which may be welded thereto, and which is internally threaded to receive the correspondingly threaded lower end of a tubular column 14, which is open at its upper end to detachably receive an extension rod 16 telescopingly and slidably received therein. In the bottom of the hollow socket 12 there is provided an annular cushioning member 18 of sponge rubber or other suitable cushioning resilient material for softening the impact of the 30 lower end of the extension rod 16 when the latter is in its lowered position.

Extending from its open upper end to a point adjacent its lower end, the tubular column 14 is provided with a longitudinal slot 20 for slidably and guidingly receiving a laterally extending projection 22 which may be integrally formed upon or may be rigidly or detachably connected to the side of the extension rod 16. This extension may conveniently take the shape of a screw-threaded bolt 22, as indicated in Figures 6 and

40 7. Preferably, the upper end of the tubular column 14 is provided with a downwardly recessed or concaved seating surface 24, whereby when the extension rod 16 is lifted and the projection 22 50 raised above the end of the slot 20, the projection and rod may be turned angularly and the projection rest upon the recess 24 to thereby securely retain the telescoping members in their extended position. As shown in Figure 9, the projection 55 22 may be turned in alignment with the slot 20 when it is desired to lower the rod into its tele-

scoping position and reduce thereby the height of the garment support column 14.

Rising from sockets 26 welded or otherwise rigidly secured to the opposite ends of the base 10 are a pair of standards 28 which may be screw-threaded for engagement in said sockets, and which are of tubular construction and open at their upper ends. Preferably, adjacent their upper ends, these standards have welded or otherwise rigidly attached thereto laterally extending sockets 30 for detachably supporting therebetween a plurality of vertically spaced bag support rods 32. Removably seated in the open upper ends of the standards 28 are the downwardly extending extremities 34 of the transversely disposed top member of a bag clamp. Adjacent its extremities, the bar 36 is provided with downwardly and outwardly extending V-shaped leg members 38 which are united by transverse bars 40.

It may thus be seen that a plurality of different size garment bags, indicated by dotted lines in Figure 1, may be suspended from the different bag support rods 32, by being folded and hung thereover, and are clamped thereto and prevented from accidental displacement from the support rods by means of the V-shaped clamp which straddles the support rods and is directly fastened to the standards 28.

A suitable fastening means for detachably securing the rods 32 to the standard sockets 30 is shown in detail in Figure 3. In this construction, it will be seen that the adjacent ends of the sockets 30 and bars 32 are internally screw-threaded for detachably receiving connecting nipples 42.

The operation of this embodiment of the invention will be readily understood. The various sizes of bags are suspended from the bag rack support rods 32 and retained thereon by the clamp as above mentioned. A garment such as a coat, as indicated in Figures 1 and 2, is suspended from its hanger, the supporting hook of which is received in the open upper end of either the tubular support column 14, if only the latter is employed, or the corresponding open upper end of the extension rod 16 if the latter is received within the column. The desired garment bag is then grasped by one edge and pulled downwardly from its support bar over and upon the garment and its hanger, until it is placed in the dotted line position shown in Figures 1 and 2. The garment may then be lifted by its hanger and removed, whereupon the device is ready for use with the next garment. Where a longer support rod is desired than that necessary for coats, or trousers, the telescoping extension rod may be positioned in the tubular column 14 and elevated to its raised position, with the lateral projection 22 resting in the seat 24 at the upper end of the column, to thereby support a dress or similar article at a greater height whereby a longer bag may be placed over the same.

As will readily be seen, this embodiment of the invention permits the bagging of garments of different sizes with the desired size of garment bag, various assorted sizes of bags being suspended in easily accessible position above the device.

Attention is now directed to the second embodiment of the invention illustrated in detail in Figures 4 and 5, and 8. In this form of the invention, a base 50 is provided which may be of similar construction to the base 10. A plurality

of tubular support columns 52, 54 and 14 are detachably secured in supporting sockets 58 which are welded or otherwise rigidly secured to the base 10, and which, if desired, may be of the same construction as the support column 14 of Figure 1. Preferably, these support columns are of different sizes, each being particularly adapted to conveniently support a particular type of garment such as pants or trousers upon the column 52, suits or coats upon column 54 and dresses upon column 14. If desired, one or more of the tubular columns, such, for example, as the column 14, may be of the same telescoping construction described with reference to the embodiment of Figure 1. Thus, the tubular column 14 may be provided with the cushioning member 18 for cushioning the descending lower end of the extension rod 16 which is provided with a laterally extending projection 22 slidably, guidingly and detachably received in the elongated longitudinal slot 20 of the tubular column 14. As in the preceding embodiment, the upper end of the tubular column is provided with a recess seat 24, see Figure 10, for receiving the lateral pin 22 to support securely the extensible rod in its uppermost position, as indicated in dotted lines in Figure 4.

As in the preceding embodiment, support standards 56 are rigidly mounted upon opposite ends of the base 50 and, intermediate their ends, are provided with a transversely extending brace rod 58. As shown in Figure 4, the upper ends of the standards are of different heights, to accommodate the staggered or shouldered arrangement of bag support rods thereon. This arrangement of rods consists of a plurality of parallel, vertically spaced and longitudinally spaced support bars 60, 62, and 64 which are respectively positioned above the columns 14, 54, and 52 for supporting garment bags thereabove. The rods 60, 62 and 64 are of one-piece integral tubular construction, with their ends attached in any suitable manner to the support standards 56, and each of the rods is provided with a removable bag clamp thereover.

As shown in Figures 4 and 8, the clamp for the rod 60 consists of a parallel bar 66 disposed above the rod 60 and having downwardly turned ends 68 which are releasably received in upstanding sockets 70 carried by a standard 56 and the extremity of the horizontal bar 60, whereby the clamp may be removed or installed as desired. As in the preceding embodiment, the clamp preferably consists of pairs of downwardly and outwardly inclined legs 72 adjacent each extremity of the bar 66, the lower ends of these legs being joined as by transverse bars 74. It will thus be seen that when a series of bags is folded upon the bar 60, the depending leg portion 72 and its transverse bar 74 maintain the bags in folded position and prevent their accidental displacement from the bar 60 in a readily understood manner. The clamp provided for the support bars 62 and 64 each consists of a transversely extending clamp rod 76, one extremity of which is journaled in a suitable socket or aperture in the vertical riser connecting adjacent parallel support rods, while its other extremity is provided with a downwardly turned end portion 78 which is detachably received in an upstanding socket 80 carried by the riser between the bars 62 and 64, and a similar socket 82 carried by the right-hand standard 56. These clamps are likewise provided with downwardly and outwardly inclined leg por-

tions 72 connected by transverse end bars 74, as in the preceding clamp described above.

Suitably carried by the standards 56 are receptacles 84 for retaining tickets or other equipment commonly required by cleaning establishments in connection with the bagging of garments, and a hook 86 for retaining string or other items. The operation of this embodiment of the invention is substantially identical with that set forth for the preceding embodiment, except that by the longitudinal displacement of the various bag supporting bars, one or more garments may be bagged at one time by one or more attendants. If desired, each of the support columns 52 and 54 may be of identical construction with the column 14, or if desired, one or more may be of the non-extensible type.

It should be here noted that the telescoping extensible supports may have the extension rod 16 either slidably received in or telescopingly and slidably received upon the outside of the support column 14, in which latter case the annular cushioning disk 18 will be in the form of a washer disposed upon the outside of the column 14. Also, the lateral projection 22 would be formed or extend inwardly from the circumference of the hollow extension rod 16.

From the foregoing, the manner of constructing and operating the device will be readily understood and its numerous advantages will be manifest. Accordingly, further explanation is believed to be unnecessary. Since numerous modifications and changes will readily occur to those skilled in the art after a consideration of

the foregoing specification and accompanying drawings it is not intended to limit the invention to the exact construction shown and described, but all suitable modifications and equivalents may be resorted to falling within the scope of the appended claim.

Having thus disclosed and described the invention, what is claimed as new is as follows:

10 A garment bagger comprising a base, a garment support extending upwardly from said base and a bag rack mounted on said base above said support, said bag rack including a plurality of parallel bag support bars at different elevation above said base, a clamp for retaining bags on said bars, said bag rack being supported between a pair of standards at opposite sides of said base, a brace connecting the top of said standards, said clamp including a V-shaped frame straddling and depending from said brace and above 15 20 said support bars.
